[57] **CLAIM**

The ornamental design for a bedstead, as shown and described.

DESCRIPTION

FIG. 1 is a perspective view of a bedstead, showing my new design;

FIG. 2 is a side elevational view;

FIG. 3 is an elevational view, showing the side not shown in FIG. 2;

FIG. 4 is a front elevational view;

FIG. 5 is a rear elevational view;

FIG. 6 is a top plan view; and

FIG. 7 is a bottom plan view thereof.

The design is characterized by the combination of the specifically configured headboard in association with the specifically configured footboard as best illustrated in FIG. 1.
